CLAIM

The ornamental design for an ear-mountable bio-sensor device, as shown and described.

DESCRIPTION

FIG. 1 is a rear perspective view of an ear-mountable bio-sensor device showing a first embodiment of our new design;

FIG. 2 is a front perspective view thereof;

FIG. 3 is a side view thereof;

FIG. 4 is a another side view thereof;

FIG. 5 is a rear view thereof;

FIG. 6 is a front view thereof;

FIG. 7 is a top view thereof;

FIG. 8 is a bottom view thereof;

FIG. 9 is a rear perspective view of an ear-mountable bio-sensor showing a second embodiment of our new design;

FIG. 10 is a front perspective view thereof;

FIG. 11 is a side view thereof;

FIG. 12 is another side view thereof;

FIG. 13 is a rear view thereof;

FIG. 14 is a front view thereof;

FIG. 15 is a top view thereof; and,

FIG. 16 is a bottom view thereof.

The over-the-ear clip of the ear-mountable bio-sensor device shown in broken lines in FIGS. 1-8 or grayed out in FIGS. 9-16 represent an environmental subject matter that forms no part of the claimed design.
